[57] CLAIM

The ornamental design for a base for telephone set, substantially as shown and described.

DESCRIPTION

FIG. 1 is a perspective view of the base for a telephone set, showing our new design;

FIG. 2 is a top plan view;

FIG. 3 is a front elevational view;

FIG. 4 is a side elevational view;

FIG. 5 is a rear elevational view; and

FIG. 6 is a perspective view of a modified embodiment thereof.

FIG. 1

FIG. 2

FIG. 3

FIG. 4

FIG. 5

FIG. 6
